UNITED STATES PATENT OFFICE.

BERNARD BORNSTEIN, OF JACKSONVILLE, FLORIDA.

SHIRT.

Application filed March 22, 1924. Serial No. 701,125.

This invention relates to shirts and more especially to a garment of this character with which soft overturned collars are to be worn. Heretofore it has been the practice 5 to sew buttons onto the front of the shirt for engagement with the flaps of the collar but these buttons become detached and lost in laundering and often pull from and injure the shirt.

10 It is an object of the present invention to provide a shirt with means whereby detachable buttons can be used for engagement with the flaps of the collar so that the objections heretofore present will be eliminated.

15 With the foregoing and other objects in view which will appear as the description proceeds, the invention resides in the combination and arrangement of parts and in the details of construction hereinafter de-

20 scribed and claimed, it being understood that changes in the precise embodiment of the invention herein disclosed may be made within the scope of what is claimed without departing from the spirit of the invention.

25 In the accompanying drawings the preferred form of the invention has been shown.

In said drawings—

Figure 1 represents a front elevation of a portion of a shirt having a collar connected 30 thereto, one of the flaps being upturned.

Fig. 2 is a rear view of one of the button engaging portions of the shirt.

Fig. 3 is a section on line 3—3, Fig. 2.

Referring to the figures by characters of 35 reference 1 designates a portion of a shirt to which a collar 2 is adapted to be attached in the usual way the points of the flaps of the collar being provided with button holes 3. Formed in the front of the shirt at 40 points directly back of the flaps attaching the collar are button holes 4 the pockets 5 of which are provided back of these button holes by attaching small pieces 6 of material along three edges of the shirt so as to bridge 45 the button holes 4. Detachable collar but-

tons 7 of any preferred kind are adapted to be inserted into the pockets 5 and thence through the button holes 4 so that the bases of the buttons will rest in the pockets 5 while the heads will project forwardly from 50 the shirt. Thus these buttons can be engaged readily by the flaps of the collar 2 by inserting them through the button holes 2. When the shirt is to be laundered the buttons can be removed. It will be noted that 55 the button holes 3 are vertically disposed in the collar 2 when the collar is in position on the shirt and that the button holes 4 are likewise vertically disposed. Thus when a shirt stud or button is inserted through the 60 registering button holes 3 and 4 a considerable relative sliding movement of the ends of the collar relative to the shirt is permitted without pulling on the shirt and distorting it. Such movement might be due to back- 65 ward pressure upon the collar by the neck when the head is thrown backward. Such an arrangement of button holes also allows for proper connection where there is slight 70 variation in the shape or size of the collar. 70

What is claimed is:—

A shirt having parallel vertical button holes in the front portion thereof adjacent the collar band and at opposite sides of the center of the shirt front, and a collar having 75 button holes in the slot portions thereof, said button holes being adapted to extend vertically in front of the respective button holes in the shirt front, each button hole in the collar adapted to receive a button re- 80 movably mounted in the adjacent button hole in the shirt, the said button holes in the shirt and collar cooperating, while in en- gagement with a button, to permit extended 85 relative up and down movement of the collar flaps and the shirt.

In testimony that I claim the foregoing as my own, I have hereto affixed my signature.

BERNARD BORNSTEIN.
